UNITED STATES PATENT OFFICE.

DONALD CAMERON, FREDERICK J. COMMEN, AND ARTHUR J. MARTIN, OF EXETER, ENGLAND.

APPARATUS FOR TREATING SEWAGE.

SPECIFICATION forming part of Letters Patent No. 634,427, dated October 3, 1899.

Original application filed May 2, 1898, Serial No. 679,522. Divided and this application filed November 26, 1898. Serial No. 697,499. (No model.)

To all whom it may concern:

Be it known that we, DONALD CAMERON, FREDERICK JAMES COMMEN, and ARTHUR JOHN MARTIN, subjects of the Queen of Great Britain, residing at Exeter, in the county of Devon, England, have invented new and useful Improvements in Apparatus for the Treatment of Sewage and other Liquids, (for which we have made application for Letters Patent 5 in Great Britain, No. 5,671, dated March 8, 1898; in France, No. 264,570, dated May 18, 1898; in Belgium, No. 135,680, dated May 18, 1898, and in Germany, dated May 20, 1898, and September 19, 1898,) of which the following is a specification.

This case is a division of our application, Serial No. 679,522, filed May 2, 1898.

This invention relates to means for filling and emptying tanks, filters, or other receptacles, which receptacles will be hereinafter referred to as "filters," and the contents of which it is desirable to be able to discharge at two or more different levels—as, for instance, where the filtered water has to be delivered upon land a part of which lies above the level of the bottom of the filter.

We will now proceed to describe our invention in connection with the accompanying drawings, in which—

30 Figure 1 is a longitudinal section, and Fig. 2 a plan view, showing an arrangement which may be employed when it is desired to discharge the effluent from the filters at two different levels.

35 According to the present invention we provide the filter with two or more discharge-valves, each having a pipe or passage delivering at the desired level. If, as shown in the drawings, there are two discharge-valves 40 1^e and 1^f they will be suspended from opposite ends of a lever 23, which will be carried at or near its center by a link 24, pivoted to another lever 25, preferably fixed on the shaft 6, and receiving its motion from 45 an actuating bucket or buckets. One bucket 7 only is shown; but it will be readily understood that, if desired, a pair of buckets may be used. The weights of the two discharge-valves 1^e and 1^f will be so proportioned that

when the lever carrying them is lifted, if 50 there is no water over the valves, the valve 1^f, delivering at the higher level, shall remain on its seat and the valve 1^e, delivering at the lower level, shall be lifted; but if the filter is full when the lever is lifted the pressure of 55 water on the lower valve 1^e shall cause it to remain on its seat, so that the higher valve 1^f shall be lifted and the contents of the filter escape thereby at the higher level. As the water in the filter is drawn off the pressure 60 on the lower valve 1^e will be reduced until a point is reached at which the weight of the higher valve overcomes that of the lower valve and the water-pressure thereon and opens the latter, discharging the remaining 65 contents of the filter at the lower level. In the drawings we have, as already stated, shown a single bucket 7 only for actuating the lever 25 at the desired times; but it will be readily understood that we do not confine 70 ourselves to this arrangement, in which it will be seen that the bucket 7 is placed on that side of the shaft 6 opposite to the discharge-valve 1^e, which will be opened by it. The rate of filling of the bucket from well 75 1^a through the pipe 9^a may be regulated, if so desired. The descent of the bucket will cause the discharge of the filter and the closing of its supply-valve 1^b, which, as shown, is carried by the lever 25, on which the bucket 80 and also the discharge-valve are mounted. The reversal of this motion will be brought about by the overflow from another filter passing through pipe 9 into the chamber 21, in which the bucket 7 is hung, the water surrounding the bucket neutralizing the weight of that in the bucket, which will ascend, the weight of the moving parts being so adjusted 85 that the discharge-valves will fall onto their seats. As soon as the chamber 21 is full its 90 contents will be released, which may be effected either by a valve connected with the lever carrying the bucket or, as shown, by a siphon 22, preferably the latter. The bucket will be emptied at the same time by the falling of the water as the discharge proceeds, 95 which will bring into action a siphon 20, connected with the bucket, whereby the contents

- of the latter will escape. In order to prevent this siphon from coming into action when the bucket is first filled, the top of the siphon will be above that of the bucket, so that no water can possibly overflow through it at that time; but when the filter fills, the filtered effluent, rising in the descending leg of the siphon, will displace the air therein through a small air-valve 20^a, thus charging the siphon, which will come into action as soon as the water in the chamber is drawn off. If desired, however, a pair of buckets mounted either on the same lever as that from which the lever carrying the valves is suspended or a separate one operating in any suitable manner may be used. It will also be understood that an additional valve or valves may be worked in the same way by means of an additional lever or levers.
20. What we claim as our invention, and desire to secure by Letters Patent, is, in apparatus for the treatment of sewage or other liquids—
1. The combination with a receptacle whose contents it is desired to discharge at two or more levels, of two or more valves for discharging such contents at the desired levels, which valves are successively opened by the action of the discharging apparatus, substantially as specified.
2. The combination with a lever for controlling the supply and discharge of a receptacle, of a second lever connected to the for-

mer and also with valves so as to effect the discharge at different levels, substantially as specified.

3. The combination with a receptacle whose contents it is desired to discharge at two or more levels, of two or more valves suspended from a lever or levers, and so adjusted as to weight that in the absence of pressure on them the lower valve will remain open while the upper valve or valves remain closed, but that with a certain pressure of water upon the lower valve an upper valve will open while the lower valve remains closed, substantially as specified.

4. The combination with a lever for controlling the supply and discharge of a receptacle, of a second lever connected to the former and also with valves so as to effect the discharge at different levels, the weights of the discharge-valves being so proportioned that when the discharge first begins the higher valve will be opened and remain open until the level of the liquid falls to such an extent that the weight of the higher valve overcomes that of the lower one, and thus closes the former and opens the latter, substantially as specified.

DONALD CAMERON.
FRED. J. COMMINS.
ARTHUR J. MARTIN.
